CLAIM

The ornamental design for a battery, as shown and described.

DESCRIPTION

FIG. 1 is a first perspective view of a battery of my new design.

FIG. 2 is second perspective view of the battery of FIG. 1.

FIG. 3 is a front view of the battery of FIG. 1.

FIG. 4 is a back view of the battery of FIG. 1.

FIG. 5 is a right-side view of the battery of FIG. 1.

FIG. 6 is a left-side view of the battery of FIG. 1.

FIG. 7 is a top view of the battery of FIG. 1; and,

FIG. 8 is a bottom view of the battery of FIG. 1.

The dash-dash broken lines in the drawings are for the purpose of illustrating portions of the article that form no part of the claimed design. The dot-dash broken lines in the drawings are for the purpose of illustrating a boundary and form no part of the claimed design.

1 Claim, 6 Drawing Sheets(56)
